NATHAN C. BUTLER, OF CLEVELAND HEIGHTS, OHIO, ASSIGNOR OF ONE-THIRD TO FRANK L. SESSIONS, OF LAKEWOOD, OHIO, AND ONE-THIRD TO ROBESON B. WOLCOTT, OF CLEVELAND HEIGHTS, OHIO.

ATTACHMENT PLUG.

Application filed September 25, 1919. Serial No. 326,188.

My invention relates to attachment plugs such as are used for connecting electric extension cords or wires to lamp sockets or other receptacles for the purpose of conducting current to portable electric translating devices.

Among the objects of my invention are the provision of an attachment plug to which the conductors may be connected without the use of solder; the provision of an attachment plug composed of only three parts; the provision of an attachment plug which can be easily manufactured at low cost and which shall be of simple but rugged and durable construction; and the provision of an attachment plug in which each of the wires connected to it leads away from its binding-screw in a direction parallel to the axis of the binding-screw and at a right angle to that portion of the wire which is under the screw head or flange which enables it to withstand strong pulls on the extension cord without being loosened from the plug.

I attain these and other objects by the use of the device illustrated in the accompanying drawings in which

Fig. 1 is a side elevation of a complete attachment plug made in accordance with my invention; Fig. 2 is a plan view of the attachment plug shown in Fig. 1; Fig. 3 is a section on line III—III of Fig. 2; Fig. 4 is a similar view to Fig. 3 but shows only the body member of the attachment plug; Fig. 5 is a plan and Fig. 6 is a longitudinal section of the headed central-terminal or contact binding-screw; Fig. 7 is a side elevation of the body member with the central-terminal binding-screw molded in place; Fig. 8 is a longitudinal section of the shell-contact member; Fig. 9 is a fragmentary plan view of a modification of my invention and Fig. 10 is a fragmentary section on line X—X of Fig. 9.

Referring to the drawings, 1 is the body member which I prefer to make entirely of insulation although its construction may be modified by molding one or more metal parts in it in the manner shown in Figs. 9 and 10, which will be further described. The body member, 1, may have an enlarged collar, 2, formed upon it. The periphery of the collar, 2, and the adjacent end of the body, 1, may be knurled or fluted in a well

known manner to facilitate the manipulation of the attachment plug. A central longitudinal aperture, 3, is provided for the reception of the wires which are to be connected to the attachment plug. At the upper end of the body, 1, as seen in Fig. 4, the longitudinal aperture, 3, is provided with an internal thread, 4, and may be provided with a counterbore, 5, for the reception of a headed central-terminal binding-screw, 6. The shank, 7, of screw, 6, is threaded to fit the threaded aperture, 4, in the body member and has a longitudinal hole, 8, extending through it. The head of screw, 6, is provided with a slot at 9 which slot at one or both of its ends extends clear through the head. The lower end of the hole, 8, may be tapered or countersunk as shown at 10 to facilitate the entrance of the wire which is to be connected to this central-terminal of the attachment plug. It will be observed that the central terminal member is detachably secured in the aperture, 3, to the body member, 1.

I prefer to make the shank of the body member, 1, of two different diameters, the larger of which is threaded as shown at 11 and terminates in an annular transverse shoulder, 12, where the diameter of the body, 1, becomes smaller as seen at 13. From the longitudinal hole, 3, I provide an outlet opening, 14, leading to the periphery of the externally threaded portion of the body member and particularly to the shoulder, 12. Upon the externally threaded shank, 11, of the body, 1, is screwed the metal sleeve or shell-contact, 15. The shell-contact is preferably made with an annular shoulder, 16, adapted, when the shell is screwed on to the body member, to coact with the shoulder, 12, to firmly bind and to contact with the end of the conductor, 17, which is to be electrically connected to the shell, 15. The other conductor, 18, which is to be secured to the central-terminal of the attachment plug passes through the longitudinal hole, 3, of the body, through the hole, 8, in the central-terminal binding-screw, 6, through the slot, 9, and under the head of the binding-screw, 6, and is secured in this position by tightening the binding-screw, 6, in the threaded hole, 4, of the body member. 19 is the insulated duplex conductor which embodies the wires leading to the attachment plug.

In Fig. 7 I have shown the insulating body member, 1, with the central-contact binding-screw, 6, molded in place. This is the manner in which I prefer to manufacture these parts although they may be manufactured in any other suitable way. In molding the binding-screw, 6, in place, it will be understood by those skilled in the art that the binding-screw is securely held in the mold while the material of which the body member, 1, is made is being molded. After the body member is molded and cured the binding-screw, 6, may be partially unscrewed to admit the wire, 18, for the purpose of connecting it to the attachment plug.

In Figs. 9 and 10 I have shown a modified construction in which there are molded in place a metal nut, 20 and a metal ring, 21. If these parts be molded in place as shown in Figs. 9 and 10 the metal nut, 20, provides a stronger and more durable thread for the binding-screw, 6, than the insulating material of the body, 1, provides, and also provides a metal shoulder, 22, to receive the pressure of the conductor, 18, which is clamped to it by the binding-screw, 6. The ring, 21, provides a metal shoulder against which the conductor, 17, may be clamped by the contact shell, 15. Projections such as shown at 23 and 24 may be formed upon the members, 20 and 21, respectively, to prevent them from twisting out of place when the contact members, 6 and 15, are tightened.

The advantages of my invention including that of providing an attachment plug having the smallest possible number of parts will be apparent to those skilled in the art.

Having thus described my invention, I claim:

1. In an attachment plug, a body member of insulating material having an externally-threaded portion and a portion of smaller diameter extending beyond said threaded portion terminating in an annular shoulder, a metal shell having an internal thread adapted to be screwed upon said threaded portion and also having an inturned flange overhanging said shoulder, said body member having a central longitudinal hole extending through it for the reception of the wires to be connected to the plug, an outlet-opening from said hole to said shoulder, one of said wires being extended out through said outlet-opening and bent around and laid upon said annular shoulder so as to be clamped thereagainst by the flange on the metal shell, and a central contact to which the other wire is connected.

2. In an attachment plug a body member of insulating material having an externally-threaded shank, a metal shell having an internal thread fitted to said externally threaded shank and an external thread adapted to fit the thread of an incandescent lamp socket, said body member having a central longi-

tudinal hole extending through it for the reception of the wires connected to the attachment plug and a transverse outlet hole for that one of said wires which is to be connected to said shell, and a headed central-contact member having a threaded shank fitting a threaded portion of said central longitudinal hole, said central contact member having a longitudinal hole and a transverse slot adapted to receive that one of said wires which is to be connected to said central contact member, means being provided for holding said wire in said slot by a clamping action.

3. An attachment plug comprising a body member of insulating material, a central-terminal binding-screw at the end thereof, and a threaded contact sleeve on said body member, said body member having a longitudinal hole for the reception of the wires connected to the plug, said central-terminal binding-screw having a central longitudinal hole and a transverse slot adapted to receive that one of said wires which is to be connected to said central-terminal, means being provided for holding said wire in said slot by a clamping action.

4. In an attachment plug a body member of insulating material having an externally threaded portion and a portion of smaller diameter extending beyond said threaded portion said threaded portion terminating in a transverse shoulder surrounding said portion of smaller diameter, a metal shell having an internal thread adapted to be screwed upon said threaded portion of said body member and an inturned flange adapted to abut upon said shoulder when said shell is screwed upon said body member, said body member having a central longitudinal hole extending through it for the reception of the wires to be connected to the plug and an outlet opening from said hole to said shoulder for that one of said wires which is to be connected to said shell, the end portion of this wire being bent around the body member and laid on said shoulder so as to be clamped thereagainst by said flange, and a central-terminal binding-screw threaded into the end of said portion of smaller diameter said screw having a central longitudinal hole and a transverse slot adapted to receive the end of that wire which is to be connected to said central terminal.

5. An attachment plug comprising an insulating body having a threaded shank; a shell screwed onto the shank; a central-contact member screwed into the end of said shank, said shank having a central longitudinal passageway extending therethrough and an outlet hole from said passageway to the periphery of said shank, and said central-contact having a slotted head and a central aperture adapted to receive the wire which is to be connected to said central-

contact, means being provided for holding said wire in said slot by a clamping action.

6. In an attachment plug, a body of insulating material having a threaded shank 5 and a transverse shoulder, a metal shell-contact member screwed on to said shank and having an annular flange at one end adapted to coact with said shoulder to bind and make contact with one of the wires connected to said plug, and a central-terminal member in the form of a headed binding-screw threaded into said body and having a central longitudinal hole and a transverse slot adapted to receive and make contact 15 with the other one of the wires connected to said plug.

7. In an attachment plug a body member having an externally threaded shank, a metal shell having an internal thread fitted to 20 said externally threaded shank and an external thread adapted to fit the thread of an incandescent lamp socket, said body member having a central longitudinal aperture extending through it for the reception of 25 the wires connected to the attachment plug and a transverse outlet opening for that one of said wires which is connected to said shell, and a headed central contact member having a shank detachably held in said central longitudinal hole in said body member, 30 said central contact member having a longitudinal hole and a transverse slot adapted to receive that one of said wires which is connected to said central contact member.

35 8. An attachment plug comprising a body member of insulating material, a central-terminal member detachably secured at one end to said body member, said body member having a longitudinal aperture for the reception 40 of the wires connected to the plug, said central-terminal having a longitudinal aperture and a transverse slot adapted to receive that one of said wires which is to be connected to said central terminal, means being provided for holding said wire in said slot 45 by a clamping action.

9. In an attachment plug a body member of insulating material having an externally threaded portion and a portion of smaller 50 diameter extending beyond said threaded portion, said threaded portion terminating in a transverse shoulder surrounding said portion of said smaller diameter, a metal shell having an internal thread adapted to 55 be screwed upon said threaded portion of said body member and having an inturned flange adapted to abut upon said shoulder when said shell is screwed upon said body member, said body member having a central longitudinal aperture extending through it 60 for the reception of the wires connected to

the plug and an outlet opening from said aperture to the periphery of said body adjacent to said shoulder for that one of said wires which is to be connected to said shell 65 and a headed central terminal member detachably secured in said central longitudinal hole to said body, said central terminal member having a central longitudinal hole and a transverse slot adapted to receive the 70 end of that wire which is connected to said central terminal.

10. In an attachment plug, a body of insulating material having a threaded shank and a transverse shoulder, a metal shell-contact member screwed on to said shank and having an annular flange at one end adapted to coact with said shoulder to bind and make contact with one of the wires connected to said plug, said body having a 80 central longitudinal aperture and a transverse outlet opening from said aperture to the periphery of said shank adjacent to said shoulder, and a central terminal-member detachably secured in said aperture to the end 85 of said body member, said central terminal-member having a head forming a shoulder adapted to coact with the end of said body member to bind and make contact with the other one of the wires connected to said 90 plug, said central terminal-member having a central longitudinal hole and having a transverse slot through said head said hole and said slot being adapted to receive that one of said wires which is connected to said 95 central terminal-member.

11. An attachment plug comprising an insulating body having a passage formed therein, a shell upon the insulating body, a conductor having electric connection with 100 the shell, a headed tubular element disposed in said passage and provided with a conductor receiving opening, and a second conductor passing through said passage into said tubular element and through said conductor receiving opening, one end of the second named conductor being confined beneath the head of said tubular element.

12. An attachment plug comprising an insulating body having a passage therein, a headed tubular element disposed in said passage, said element having a slot formed in the head thereof, a conductor passed through said passage and the tubular member, one end of the conductor being bent 110 into said slot and disposed beneath the head of said element and maintained in electrical contact therewith, a shell upon said insulating body, and a second conductor having 115 electrical connection with said shell.

In testimony whereof I affix my signature.
NATHAN C. BUTLER.
